SEWING MACHINE

Ramon Casas Robert, Geneva, Switzerland, assignor to Mefina S. A., Binningen, Switzerland, a corporation of Switzerland

Application March 31, 1949, Serial No. 84,602
In Switzerland December 20, 1948

5. Claims. (Cl. 112—254)

1

In a sewing machine, the thread feeding the needle passes first through a guide fixed at the end of an arm, then through a tension device before passing through the thread-puller, and finally through a guide fixed to the needle-carrier.

In almost all known machines, the thread tension device is situated on the fore face of the needle-carrying arm, that is to say on the wall facing the operator. Now, practice has shown that the thread tension device is a source of great eye strain for the operator.

Indeed, this thread tension device intercepts the view of the operator watching the running of the work under the presser foot, and owing to the fact that this tension device is vibrating all the time and is situated closer to the operator's eye than the work, it constitutes a great hindrance, because the lower part of the presser foot is visible only to the operator's left eye. Thus the tension device induces the operator to squint thereby provoking a great eye strain.

Some designers have endeavored to remedy this inconvenience by placing the tension device on the rear wall or on the front face of the needle-carrying arm, but such an arrangement is a source of difficulties in construction and mechanical drawbacks which make it preferable to place the tension device on the arm's fore wall.

The present invention relates to a sewing machine including a column bearing an arm at the end of which are mounted the needle-carrier and the thread-puller, both driven in a to-and-fro movement by transmission members housed in said arm, the latter having on its rear face a support for a thread reel and a thread-guide which latter is located at the end of the arm, at the height of said support. This machine differs from the known machines in that it has means for safeguarding the thread over the full length of its path between said guide and the thread-puller.

The attached drawing shows diagrammatically and by way of example a form of construction of a sewing machine in accordance with the invention.

Fig. 1 is a view of the end face of the needle-carrying arm;

Fig. 2 is a perspective view of the front wall of the needle-carrying arm;

Fig. 3 is a perspective view of the rear wall of the needle-carrying arm;

Fig. 4 is a top view of the needle-carrying arm;

Fig. 5 is a part cross-section view along the line V—V of the Fig. 1.

2

Sewing machine represented on the drawing includes a column 1 bearing an arm 2 at the end of which is mounted a needle-carrier 3 and a thread-puller 4, both driven in a to-and-fro movement by a mechanism (which is not shown) housed in the arm and connected to a driving motor (not represented) housed in the column. The rear face of the arm's column has a flat surface 5 carrying two fixed spindles 6 and 7 intended to receive two spools 8 and 9. A thread-guide 10 is fixed on the rear wall of arm 2, at the end of the said arm, approximately in the transversal middle plane of the reels.

The arm 2 has an end face 11, provided with a protruding part 12, from which emerges laterally the thread-puller 4. The end of the latter, in its extreme upper position, is approximately situated in a horizontal plane *a* passing through the thread-guide 10.

20 The protruding part 12 has a general V-shape, with a rounded lower end. The front and rear surfaces of the V-shaped part 12 are connected at their upper portions by a top wall 13 of semi-cylindrical form and aligned with the upper wall 25 of the arm 2. The V formed by the protruding part 12 is symmetrically arranged in relation to a vertical longitudinal plane *b* passing through the center of the arm 2, and the thread-puller and the thread-guide are symmetrically arranged on either side of this plane. Thus, seen from the end (Fig. 1) the arm has a very marked symmetry in relation to the plane *b*, which helps to impart to the sewing machine an elegant appearance pleasing to the eye.

35 The lower part of the protuberance 12 covers a tension device 14, symmetrically arranged in relation to the plane *b*, and of which the axis of the shaft 15 coincides with the axis of the bottom semi-cylindrical wall 16 forming the lower 40 part of the V. This cylindrical wall has a slot 17 intended for the passage of the thread. The ends 18 and 19 of this slot are so shaped as to constitute guides for the thread, entering and leaving the tension device.

45 The slope of the rear and front walls 20 and 21 of the protuberance 12 is such that the thread-guide 10 and the end of the thread-puller in its extreme upper position are situated in line with said slopes. Thus, the portions of thread *e* and *f* run along these walls 20 and 21 close to the end face 11 of the arm (Fig. 5), so that the thread

50 run along these walls 20 and 21 close to the end face 11 of the arm (Fig. 5), so that the thread is efficiently safeguarded against any accidental catching risking either damage to the thread, or hindrance to the proper working of the switch formation device.

In addition, the path followed by the end of the thread-puller is almost parallel to the front wall 21 of the protuberance 12, a slot 23 being provided in this wall to permit the movement of the thread-puller. The end of the thread-puller extends only in its extreme upper position beyond the cylindrical surface formed by the arm 2 in order to allow the passage of the thread, but, as far as possible, in all its other positions it is nearly concealed. An eyelet 24 is fixed to the lower part of wall 21 in order to keep the thread portion *g*, situated between the end of the thread-puller and this eyelet, close to the walls 21 and 11. Thus, this portion *g* of the thread is also efficiently safeguarded against any accidental risks of damage to the sight of the operator watching the needle's work. The result is, that with a sewing machine such as described with reference to the attached drawing, work is far less tiring for the operator's eyes than with a machine of known type provided with a tension device arranged on the fore side of the needle-carrying arm.

Finally, also for the purpose of still safeguarding as far as possible, the portion of thread *h* situated between the reel and the thread-guide 10, the latter is arranged parallel with and very close to the cylindrical surface of the arm 2, slightly below or almost at the height of the horizontal diametrical plane *a*.

From above description and by examining the attached drawing, one can realize the advantages offered by a sewing machine in accordance with the invention over a sewing machine of known type in which the thread is not safeguarded in any way and can therefore be caught inadvertently either by a ring worn by the operator, or by buttons on the work being done.

A form of construction of the machine in accordance with the invention has been described by way of example, but it is clear that slight variations in construction could be provided for, whilst remaining within the scope of the invention. Thus, it is not necessary for the protruding part 12 to be arranged symmetrically in relation to the vertical plane *b*. However, such an arrangement is advantageous from the point of view of appearance. One could also provide the protruding part with rims overhanging the walls 20 and 21, so as to form with the end face 11 two lateral grooves in which would be housed the portions of threads *e*, *f* and *g*, as well as the end of the thread-puller during the greatest part of its travelling.

I claim:

1. A sewing machine including a column bearing an arm, a needle-carrier and a thread-puller mounted at the end of said arm and actuated in a to-and-fro movement, a spool support located on the rear wall of said arm and a thread-guide arranged at the end of said arm at the height of said spool support, a part protruding with respect to the end face of said arm disposed for safeguarding the full length of the thread path located between said guide and said thread-puller which merges laterally from said protruding part on the front of said arm, said thread-guide and the end of said thread-puller in its extreme position, being situated almost in a same horizontal plane and on either side and approximately at an even distance from a longitudinal middle plane of said arm, a tension device for the thread covered by said protruding part, and a shaft for said tension device having its axis located in said longitudinal plane of said arm,

said protruding part having front and rear walls and being of the general shape of a V of which the lower angle is rounded whereby the path of said thread from said guide to said end of the thread-puller in its upper position has the general shape of a V arranged symmetrically in relation to the said longitudinal plane.

2. A sewing machine including a column bearing an arm, a needle-carrier and a thread-puller mounted at the end of said arm and actuated in a to-and-fro movement, a spool support located on the rear wall of said arm and a thread-guide arranged at the end of said arm at the height of said spool support, a part protruding with respect to the end face of said arm disposed for safeguarding the full length of the thread path located between said guide and said thread-puller which merges laterally from said protruding part on the front of said arm, a tension device for the thread covered by said protruding part, a shaft for said tension device having its axis located in a longitudinal middle plane of said arm, said protruding part having front and rear walls and being of the general shape of a V of which the lower angle is rounded, and guiding elements for the thread at the entrance and at the exit of said tension device located in the front and rear walls of said V-shaped protruding part.
3. A sewing machine including a column bearing an arm, a needle-carrier and a thread-puller mounted at the end of said arm and actuated in a to-and-fro movement, a spool support located on the rear wall of said arm and a thread-guide arranged at the end of said arm at the height of said spool support, a part protruding with respect to the end face of said arm disposed for safeguarding the full length of the thread path located between said guide and said thread-puller which merges laterally from said protruding part on the front of said arm, said thread-guide and the end of said thread-puller in its extreme position being situated almost in a same horizontal plane and on either side and approximately at an even distance from a longitudinal middle plane of said arm, a tension device for the thread covered by said protruding part, a shaft for said tension device having its axis located in said longitudinal plane of said arm, said protruding part having front and rear walls and being of the general shape of a V of which the lower angle is rounded, guiding elements for the thread at the entrance and at the exit of said tension device located in the front and rear walls of said V-shaped protruding part, whereby the part of the thread path between said thread-guide and said entrance guiding element as well as the part of the thread path between said exit guiding element and the end of said thread-puller, in its upper position, are both situated in an angle formed by the front and rear walls of the V-shaped walls protruding part on the one hand and by said end of said arm on the other hand.
4. A sewing machine including a column bearing an arm, a needle-carrier and a thread-puller mounted at the end of said arm and actuated in a to-and-fro movement, a spool support located on the rear wall of said arm and a thread-guide arranged at the end of said arm at the height of said spool support, a part protruding with respect to the end face of said arm disposed for safeguarding the full length of the thread path located between said guide and said thread-puller which merges laterally from said

protruding part on the front of said arm, said thread-guide and the end of said thread-puller in its extreme position being situated almost in a same horizontal plane and on either side and approximately at an even distance from a longitudinal middle plane of said arm, a tension device for the thread covered by said protruding part, a shaft for said tension device having an axis located in said longitudinal plane of said arm, said protruding part having front and rear walls and being of the general shape of a V of which the lower angle is rounded, said front and rear walls of said V-shaped protruding part being connected by a bottom wall, having the shape of a semi-cylinder of approximately the same radius and the same center as the said tension device, and a slot in said semi-cylindrical wall located in the plane of the thread path for the passage of said thread.

5. A sewing machine including a column bearing an arm, a needle-carrier and a thread-puller mounted at the end of said arm and actuated in a to-and-fro movement, a spool support located on the rear wall of said arm and a thread-guide arranged at the end of said arm at the height of said spool support, a part protruding with respect to the end face of said arm disposed for safeguarding the full length of the thread path located between said guide and said thread-puller which merges laterally from said protruding part on the front of said arm, said thread-guide and the end of said thread-puller in its extreme position being situated almost in a same horizontal plane and on either side and

approximately at an even distance from a longitudinal middle plane of said arm, a tension device for the thread covered by said protruding part, a shaft for said tension device having an axis located in said longitudinal plane of said arm, said protruding part having front and rear walls and being of the general shape of a V of which the lower angle is rounded, guiding elements for the thread at the entrance and at 10 the exit of said tension device located in the front and rear walls of said V-shaped protruding part, said front and rear walls of said V-shaped protruding part being connected by a bottom wall, having the shape of a semi-cylinder of 15 approximately the same radius and the same center as the said tension device and, a slot in said semi-cylindrical wall extending up to the height of said entrance and exit guiding elements of said tension device.
